UNITED STATES PATENT OFFICE.

FELIX MEYER, OF NEW YORK, N. Y.

DESIGN FOR LACE.

53,019.

Specification for Design.

Patented Feb. 25, 1919.

Application filed January 16, 1919. Serial No. 271,524. Term of patent 3½ years.

To all whom it may concern:

Be it known that I, FELIX MEYER, a citizen of the United States, residing at New York, New York county, and State of New York, have invented a certain new, original, and ornamental Design for Lace, of which the following is a specification.

Said design consists in a lace pattern, as illustrated in the accompanying drawing, wherein is shown a section of a piece of lace in which the figures constituting the design are shown, it being understood that these figures are multiplied indefinitely in accordance with the length of the piece of lace.

What I claim as new is:

The design for lace as herein shown and described.

In witness whereof, I have hereunto set my hand and seal at New York, N. Y., this fifteenth day of January, A. D. nineteen hundred and nineteen.

FELIX MEYER. [L. S.]
